COLLAPSIBLE TENT.

Application filed May 6, 1925. Serial No. 28,325.

This invention relates to collapsible tents. The general object of the invention is to provide an improved collapsible tent and frame which is readily collapsed but which when erected, is solid and substantial.

A further object of the invention is to provide a collapsible tent and frame wherein the parts are extremely light and durable and wherein these parts fold into small bundles when the tent is collapsed.

Other objects of the invention will be apparent from the following description taken in connection with the accompanying drawings wherein Fig. 1 is a perspective view showing my improved frame; Fig. 2 is a view similar to Fig. 1 showing the upper portion of the frame partly collapsed; Fig. 3 is a view similar to Fig. 2 showing the manner in which the cross members are collapsed; Fig. 4 is a side elevation of the collapsed frame of the tent; Fig. 5 is a longitudinal section showing the folding joint for the corner poles; Fig. 6 is a transverse section of the folding joint for the corner poles; Fig. 7 is an elevation of the corner pole joint with the parts extended; Fig. 8 is a view similar to Fig. 7 showing the corner pole folded; Fig. 9 is a perspective view of a connecting brace; Fig. 10 is a fragmentary view showing the brace and its associated parts; Fig. 11 is a top plan view showing the brace with the cooperating parts in extended position; Fig. 12 is a detail partly in section showing another use of the brace; Fig. 13 is a fragmentary detail showing the manner in which the parts are connected; Fig. 14 is a top plan view of one of the connections; Fig. 15 is a fragmentary perspective view showing one of the joints; Figs. 16 and 17 show the supporting members together with the links for securing them in position; Fig. 18 is a perspective view showing details of securing the side braces; Fig. 19 is a fragmentary perspective view showing the bottom of the corner posts with the securing stake; Fig. 20 is a fragmentary detail showing the manner in which the top brace folds; Fig. 21 is a fragmentary perspective view showing the manner in which the tent is secured to the frame; Fig. 22 is a perspective view of the completed tent with the bottom inserted therein; Fig. 23 is an enlarged detail showing the manner of securing the tent side wall and Fig. 24 is a fragmentary detail in perspective showing the manner in which

the bottom of the tent is secured to the corner posts.

Referring to the drawing by reference characters, I have shown a tent frame at 10. This frame comprises corner posts 11 and the top structure indicated as an entirety at 12. Each of the corner posts is preferably constructed of light wood or similar material and intermediate the length thereof is provided with a folding joint shown in detail in Figs. 5 to 8.

Referring to these figures it will be seen that the corner posts are shown as provided with flat sides 14 and with curved ends 15. The hinged joint is secured by providing connecting link member 16 on each side of the corner posts. The members are pivoted to the adjoining portions of the corner posts by rivets or other fastening means 17. Stop pins 18 on the corner posts which engage shoulders 19 which are arranged on one of the connecting members 16 of each pair, serve to limit the opening movement. The parts are held in straightened relation by means of a sliding sleeve 20 which is shown in engaging position in Fig. 5.

The corner posts are connected by cross members 25. These cross members each comprise a pair of portions 26 and 27 which are pivoted at 28. One of the members is notched as at 29 to fit a bent over tongue 30 on the other member to limit the movement of the members in one direction.

The member 26 is secured on the outside of a corner angle member 31 while the member 27 is secured to the inside of the same angle member 31. The corner angle members are shown in detail in Fig. 14 and it will be noted that these members pass through the posts 11 and are held by a rivet 31'.

In order to brace the members 26 and 27 when in straightened position, I provide angle braces 35 each comprising two members pivotally connected at 36 and provided with a stop 37 which is similar to the stop 30 previously described. The upper brace 35 is secured to a pivot member 38 on the cross member 26 while the lower brace 35 is secured to a pivot 39 on an angle member 40. A similar angular brace is secured to the portion 27 as shown at 41. This brace has the upper portion thereof arranged on the inside of the member 27 by a pivot 42 while the lower portion is pivoted to an angle member 42', it will be noted that the relation

of the brace 41 is the reversal of the brace 35 and that there are four pairs of the braces 35 and 41.

In addition to the cross members 25 the corner posts are connected by rafters which extend from each corner post. Each rafter is composed of two pivotally mounted portions 50 and 51, which are united by a pivoted joint 52 best shown in Fig. 2. This pivoted joint is similar to the joint 29 and 30 previously described and shown in Fig. 15.

The portion 50 of the rafters is provided with an angularly arranged end 53 which is pivoted as at 54 to the post 11 as shown in Fig. 20. The upper end of each of the portions 51 of the rafters is connected to a center block 55 shown in Fig. 9.

In order to hold the rafters in erect position as shown in Fig. 1, I provide brace members 56. Each of these brace members is connected at its outer end to one of the portions 51 of the rafters and at the inner end is connected to a center block 60 which is in all respects constructed in the same manner as the center block 55 is turned upside down with respect to the block 55.

The brace members 56 when in operative position have their center blocks 60 below the point of attachment of the brace members to the portions 51 of the rafters so that there will be no tendency of the brace members to collapse until the center block 60 is raised above the dotted line shown in Fig. 1.

To collapse the frame the center block 60 is first pushed upwardly thus enabling the rafter braces 56 to be pushed upwardly about their pivot.

40 The rafter sections 50 and 51 are then moved downwardly as shown in Fig. 2.

The straight relation of the braces 35 is next broken by pushing the pivoted joint 36 upwardly. Simultaneously the cross members 25 have their straight relation broken by pushing down on the pivot 28.

The parts are so proportioned that after the preliminary movement described is made they will quickly fold until the corner posts 11 are juxtaposed after which the sleeves 20 may be moved away from the links 16 and the corner posts themselves may then be folded.

In Fig. 2 I have shown the manner in which the rafter structure collapses while in Fig. 3 I have shown the manner in which the cross members collapse but it will be understood that this is merely for the purpose of showing the manner in which the parts fold and in practice I prefer to combine the cross members and the rafters in one structure.

The cover or tent proper which is adapted to be used with my frame preferably comprises a roof portion 61 and side walls 62.

The side walls 62 are arranged in position by means of hooks 64 which engage over the cross members 27 as shown in Figs. 21 and 22. After the side walls are secured the top 61 may be placed in position and secured in any desired manner.

A bottom for my tent is shown in Figs. 22 and 24. This bottom comprises a bottom portion proper 66 and a side 67. The sides 67 are provided with eyelet members 68 and when the tent is erected and the floor is in place, are adapted to engage hooks 70 disposed in the corner posts 11.

From the foregoing description it will be apparent that I have provided an improved collapsible frame for tents which is extremely simple and which can be economically manufactured.

Having thus described my invention, I claim:

1. In a folding frame for collapsible tents, the combination with corner posts, cross members and folding rafters, each of said rafters being pivotally connected at its lower end with the upper end of one of the posts and adapted to fold parallel therewith, and attached at the other end to a center block, said rafters each composed of two sections pivotally connected together, said rafters being adapted to collapse upon moving their pivotal connection downwardly.

2. A collapsible tent frame comprising hinged corner posts, folding cross members and folding rafters, said cross members being pivotally connected with the posts adjacent to their ends and each composed of two sections pivotally connected with each other, folding braces pivotally connected with the posts and with the cross members at the corners of the frame and each brace composed of two sections pivotally connected with each other, said rafters being pivotally connected at their lower ends with the upper ends of the posts and adapted to fold parallel therewith and parallel with the cross members and brace members, said rafters being attached at their upper ends to a center block, said rafters each composed of two sections pivotally connected and brace members for said rafters, said rafter brace members each comprising two pivoted sections each having one end attached to a rafter and the other end attached to a center block, said center block being arranged at one side of the plane which passes through the connection between the rafter braces and the rafters.

3. In a folding frame for collapsible tents, corner posts, corner members and rafters connected together, each of said rafters being connected at one end to a corner post and at the other end to a center block, said rafters each comprising two parts permanently and hingedly connected and adapted to fold downwardly, said cen-

ter block comprising a cruciform member having one end of each rafter pivotally mounted on an arm of said member.

4. In a folding frame for collapsible tents, 5 corner posts, corner members and rafters, each of said rafters being connected at one end to a corner post and at the other end to a center block, said center block comprising a cruciform piece of metal having one 10 end of each rafter pivotally mounted on an arm thereof, and rafter brace members connected at one end to the rafters intermediate the ends of the rafters and connected at the other end to a second center block.
- 15 5. In a collapsible tent frame, corner posts, cross members and rafters on said corner posts, means to secure said cross members to said corner posts, said means comprising strips of metal extending through said 20 corner posts and pivotally connected to said cross members, the cross member on one side of a post being arranged on one side of the strip and the cross member on the other side of the same post being arranged on the other 25 side of the strip.

6. A folding frame for a collapsible tent comprising corner posts, cross members and

rafters, said cross members and said rafters each composed of two sections permanently and hingedly connected to each other and 30 permanently hinged to the corner members, and adapted to be folded to lie alongside said corner posts, the hinge of said rafter being mounted to move downwardly when the frame is collapsed.

7. A collapsible tent frame comprising corner posts, means connecting said corner posts to hold said frame in erect position, each of said corner posts comprising a pair 35 of sections permanently and hingedly connected together said hinged connection comprising a link permanently pivoted to each of said sections, said link having notched portions forming shoulders thereon at each end thereof, said sections having stop pins 40 thereon adapted to engage said shoulders when the corner post is straightened and a slide movable over said joint and adapted 45 to surround the same to hold the parts in straightened position.

In testimony whereof, I hereunto affix my signature.

HARRY F. SNYDER.
